UNITED STATES PATENT OFFICE

162,924

SHRIMP DEVEINER

Walter Frederick William Becherer,
Milwaukee, Wis.

Application September 29, 1949, Serial No. 5,214

Term of patent 14 years

(Cl. D44—29)

To all whom it may concern:

Be it known that I, Walter Frederick William Becherer, a citizen of the United States of America, residing at Milwaukee, in the county of Milwaukee, and State of Wisconsin, have invented a new, original, and ornamental Design for a Shrimp Deveiner, of which the following is a specification, reference being had to the accompanying drawing, forming a part thereof.

In the drawing:

Fig. 1 is a view from the underside of a shrimp deveiner showing my new design,

Fig. 2 is a perspective view of my new design, and

Fig. 3 is a three quarter side perspective view of my new design.

I claim:

The ornamental design for a shrimp deveiner, as shown.
WALTER FREDERICK WILLIAM BECHERER.
